UNITED STATES PATENT OFFICE

2,438,549

APPARATUS FOR TREATMENT OF TRAVEL-
ING MATERIALS WITH FLUID MEDIA

William J. Elvin, Frostburg, and Max A. Shaffer,
Cumberland, Md., and Elmer R. Stahl, Meyers-
dale, Pa., assignors to Celanese Corporation of
America, a corporation of Delaware

Application January 26, 1944, Serial No. 519,822

2 Claims. (Cl. 68—5)

1

This invention relates to the treatment of artificial yarns and other filamentary materials, and relates more particularly to improvements in apparatus in which artificial yarns and other filamentary materials are subjected to treatment with fluids under pressure and stretched to improve their tenacity.

An object of this invention is the provision in a yarn stretching apparatus of means for exhausting from the atmosphere steam or other vapors escaping through an orifice in the treating chamber of said apparatus.

Another object of this invention is the provision, in the treating chamber of yarn stretching apparatus, of a novel jet for directing the steam or other vapors escaping therefrom away from the yarns passing therethrough.

A further object of this invention is to provide a device for cooperating with the jet in the treating chamber of the apparatus for removing and condensing steam or other vapors escaping from said jet, and for collecting condensate leaking therefrom.

Other objects of this invention, together with certain details of construction and combinations of parts, will appear from the following detailed description.

In devices for improving the tenacity of artificial filaments, threads, yarns and other materials wherein said materials are stretched during their passage through a chamber containing steam, solvent vapors or hot water under pressure, the materials treated leave the chamber through small orifices and unless special precautions are taken a flow of steam or other vapor from the chamber through the orifices takes place. This vaporous current may exert an undesirable tension on the materials, particularly when the pressure in the treating chamber is high, since the vaporous currents issuing from the orifices may persist for some distance along the path of the materials. These currents may also prevent rapid cooling of the materials when they emerge from the treating chamber. Furthermore, the steam or vapor escaping into the atmosphere fogs the same and may even cause physical discomfort to those working in the room. The steam or vapor escaping into the atmosphere condenses on to the apparatus, walls and floor with obvious disadvantageous results.

We have now discovered that the foregoing disadvantages may be substantially eliminated by diverting the vaporous current from the materials as they pass into the atmosphere and by exhausting the steam or vapor and collecting the condensate. In accordance with this invention, this

2

may be effected by means of a novel jet for the passage of the materials, which jet is positioned at an angle in an opening in the treating chamber whereby the steam or other vapor is diverted from the path of the materials into an exhaust device through which the steam or vapor may be led to the air outside of the room or, in the case of vapors, into a recovery system.

In one form of our invention, the jet may be formed by drilling a hole in a piece of metal or other suitable material at right angles to the surfaces thereof, and the jet positioned at an angle in an opening in the end plate of the treating chamber, the opening in the end plate being so formed as to retain said jet at an angle. When this jet is in operation the vapor or gas passes through the same at an angle to the horizontal, preferably in a downward direction, and the material passes through the jet opening in a straight line.

In another modification of this invention, the jet may comprise a piece of metal or other suitable material in which the hole is drilled at an angle to the horizontal, in which case the hole is of sufficient size to permit the material to pass therethrough in a straight line. This jet is placed in the opening in the end plate of the treating chamber so that it is in the same plane as said end plate.

In the drawing wherein the preferred embodiment of our invention is shown,

Fig. 1 is a side elevational view showing the exhaust device in position with respect to our novel jet in the treating chamber,

Fig. 2 is a cross-sectional view of the end of a treating chamber showing our novel jet, and

Fig. 3 is a detail view of a section of a plate showing a series of jets extending across the length thereof.

Like reference numerals indicate like parts throughout the several views of the drawing.

Referring now to the drawing for a more detailed description of our invention, a table 1 is shown supporting a yarn treating device, generally indicated by reference numeral 2, carried by suitable supports 3. The yarn treating device may be of any suitable design such as, for instance, that shown in U. S. Patent No. 2,142,721 to Dreyfus et al., or a two-compartment yarn treating device such as that shown in the drawing.

The latter yarn treating device comprise a feeding compartment 4 and a substantially closed steam compartment 5, usually cylindrical in shape, wherein the yarn to be treated is conditioned by means of steam, solvent vapor, or water under pressure. The compartment 5 may have

suitable fluid connections, valves and gauges (not shown). The compartment 5 may comprise a cylinder 6 having a head 7 integral therewith against which an apertured plate 8 is held by ring 9 and tie bolts 10. Plate 8 may have one or more apertures therein. Suitable gaskets 11 may be employed on each side of plate 8 to form an adequate seal. Mounted in each aperture of plate 8 is a jet 12 the orifice of which is usually of extremely small bore. Thus, for 30 denier yarn the bore is about 0.019 of an inch while when treating a yarn with a total denier of 440 an orifice with a bore of about 0.037 of an inch may be employed. The length of the bore may be from about $\frac{1}{8}$ to $\frac{1}{4}$ inch. The jets 12 are mounted in the plate 8 so that the axial line of the bore is at an angle to the path of travel of the yarn and the direction of the axial line is preferably downward so that the jet directs any escaping vapor downward into the mouth 13 of an exhaust device, indicated generally by the reference numeral 14. The plate 8 may contain from 1 to 100 or more jets equally spaced in a row or rows across the same, as is shown in Fig. 3. The jets may be removable so that they may be changed to accommodate any size or shape of material being treated.

The exhaust device may comprise a stack 15 that extends up through the roof of a building and may have suitable rain and wind shields 16 or it may extend into an exhaust conduit (not shown) of the general air conditioning apparatus for the room. The length and slope of the stack will determine whether a fan need be employed to keep a current of air moving up the same. One stack may be employed for each stretching device or several stretching devices may be connected to each stack by means of branching horizontal conduits, one of which is shown at 17. The conduits 17 are preferably positioned below the jets 12 and are provided with an end portion 18 hinged at 19 to either the table 1 or to the conduit 17. The hinged end portion 18 is provided with a mouth 13 formed by terminating the portion with the top side shorter than the bottom side. The hinged end portion may be lowered to the table 1 while threading up the device with the yarn 21 and then as the steam is turned on in the treating chamber 5 it is swung up and held in position by a pivoted catch 22. It may also be lowered to remove any condensate collected therein. The yarn 21 is drawn from the chamber above the conduit where it may readily be seen and manipulated since the escaping vapor is directed into the mouth 13 of the conduit and exhausted from the atmosphere or pulled to a vapor recovery system.

This invention is applicable to all textile machines employed in the treatment of yarns, filaments or threads with steam or other vapor, such as vapors of solvent and softening agents, for artificial yarns. Examples of such vapors are those comprising acetone, ethyl acetate, etc., for use with textiles containing an organic derivative of cellulose, such as cellulose acetate, and phenol, formaldehyde, etc., for use with textiles containing polyamide linear condensation products. Although, as stated above, this invention may be employed in connection with many textile operations, it is particularly adapted to those operations in which textile materials containing an organic derivative of cellulose are treated with steam under pressure, as in a crepe twisting operation or in a stretching operation. In both

of these operations, it is of great importance that the duration of contact between the yarn and steam be accurately controllable. In this respect, this invention has the added advantage of removing the steam from the yarn immediately at the exit end of the treating chamber, as well as preventing fog and condensation.

While the present apparatus is particularly effective in the treatment of yarns having a basis of cellulose acetate, it may be employed in the treatment of filamentary materials having a basis of other materials, especially thermoplastic materials having a basis of other organic derivatives of cellulose, linear polyamide condensation products and synthetic resins. Examples of other organic derivatives of cellulose are cellulose formate, cellulose propionate, cellulose butyrate, cellulose ethers such as methyl cellulose, ethyl cellulose and benzyl cellulose.

It is to be understood that the foregoing detailed description is given merely by way of illustration and that many variations may be made therein without departing from the spirit of our invention.

Having described our invention, what we desire to secure by Letters Patent is:

1. Apparatus for the treatment of travelling materials with fluid media comprising, in combination with a compartment for receiving treating fluid and having an end wall having an aperture therein, a jet having a bore of smaller diameter than said aperture extending axially therethrough through which the treated materials issue from said compartment into the atmosphere, said jet being arranged in said aperture so that the bore slopes away from the path of the travel of the materials therethrough so as to cause fluid issuing from said jet to flow in a direction away from the materials.

2. Apparatus for the treatment of travelling materials with fluid media comprising, in combination with a compartment for receiving treating fluid and having an end wall having an aperture therein, a jet having a bore of smaller diameter than said aperture extending axially therethrough through which the treated materials issue from said compartment into the atmosphere, said jet being held at an angle in said aperture so that the bore slopes away from the path of the travel of the materials therethrough so as to cause fluid issuing from said jet to flow in a direction away from the materials.
